CATHETER WITH BALL VALVE

Ragnar Wahlbeck, New York, N. Y.

Application December 13, 1949, Serial No. 132,643

4 Claims. (Cl. 128—232)

1

This invention relates to new and useful improvements in catheters, and has more particular reference to an improved valve construction and operation for catheters.

Heretofore, catheters have been constructed with valves which were either inconvenient to operate, or after some use became inoperative. This invention particularly proposes a new valve construction which is exceptionally simple to manipulate and which will remain operative in this way as long as the catheter itself lasts.

The new improved catheter with valve is characterized by a rubber bag which may be inflated with a liquid under pressure. This bag is provided at its top with a neck portion into which a nozzle or tip may be connected. This nozzle or tip may be integral with the neck portion, or may be of the hard rubber type generally used and merely connected with the neck portion. A dominating feature of the invention resides in forming said neck portion with downwardly and outwardly tapering sides, and providing a light ball within said rubber bag which will float in said liquid and become wedged into said tapering sides of the neck portion when said bag is filled with said liquid to its neck portion, so as to confine said liquid in the bag in a manner so that said ball may be manually forced downwards out of said neck portion by flexing the neck portion with the fingers in order to release said confined liquid during the use of the catheter. It is suggested that this light ball be of rigid type plastic material so as to be smooth and durable. Obviously, the ball will last indefinitely and will function as long as the rubber bag of the catheter is usable.

The invention also proposes the provision of means by which a supply of liquid may be connected with the neck portion of the bag for filling the bag. It is contemplated that these means include a tube connected with or integral with said neck portion, and a rubber pipe connector may be of a number of different designs and shapes and may operate in any number of different ways as long as it may be engaged upon a faucet or other supply of liquid in order to guide the liquid into the rubber bag with sufficient pressure for inflating the bag. It is proposed that a nozzle or tip generally used with catheters be inserted into the top of said tube, or that it be integral with the tube.

Another object of this invention resides in providing the rubber bag with a large opening through which the ball may be easily inserted into the bag, and then to provide a satisfactory

2

plug or means for closing said opening so that the bag may hold water under pressure. Since the ball is of larger diameter than the neck portion of the bag it cannot very well be inserted through the neck portion and it is for this reason that the auxiliary opening is provided in the bag.

Another object of the invention is the construction of a device as described which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

20 Fig. 1 is an elevational view of a catheter constructed in accordance with this invention, certain dot and dash lines being added to this view to indicate different positions of certain of the parts, and certain parts being illustrated broken to disclose interior parts.

Fig. 2 is an enlarged detailed view of the bottom portion of Fig. 1.

Fig. 3 is a side elevational view of another catheter embodying the same invention.

30 The catheter illustrated in Figs. 1 and 2 includes a rubber bag 10 of sufficiently thin latex so that it may be inflated with liquid under pressure. Said rubber bag 10 is formed at its top with a neck portion 11 to which a nozzle or tip 12 may be connected. In this particular form of the invention a tube 12 is integral with the neck portion 11 and extends upwards and terminates in a nozzle 13. A stiffening tube 14 of flexible plastic material is forced into the tube 12 to provide the necessary rigidity required in inserting the tube 12 into a body cavity.

40 The neck portion 11 has downwardly and outwardly tapering sides 15. A light ball 16, preferably of rigid plastic material, is disposed within said bag 10 and is sufficiently light to float in a liquid with which the bag 10 is filled. This ball 16 is sufficiently large so that when it floats to the top of the bag 10, when the latter is filled with the liquid, it becomes wedged into the tapering sides 15 of said neck portion 11, so as to confine said liquid in the bag 10. The ball 16 may be manually forced downwards out of said neck portion 15 by flexing said neck portion 15 with the fingers in order to release said confined liquid.

45 Means is associated with said neck portion 15

for connection with a faucet or pipe or other supply of liquid by which the bag 10 may be filled. This means comprises said tube 12 and a rubber pipe connector 18 slidably mounted on the tube 12. This pipe connector 18 is illustrated in full lines in Fig. 1 engaged over the neck portion 15. It is provided with a plurality of external circular ribs 19. When used it is slipped up to the top of the tube 12 and then turned inside out so as to be directed upwards above the nozzle 13 as indicated by the dot and dash lines 18. It may then be engaged upon the bottom of a faucet or another pipe. Moreover, in this position the connector may act as a funnel through which medication may be poured from a bottle through the nozzle 13 and into the bag 10. The ribs 19 serve to better grip a faucet or pipe.

Said bag 10 is provided with an opening 20 through which the ball 16 may be easily inserted into the bag 10. Means is provided for closing this opening 20. This means consists of a rubber plug 21 having a peripheral groove 22. The edge portion 23 of the bag 10 which surrounds the opening 20 is engaged into said groove 22. A rubber clamp ring 24 engages around the edge portion 23 and forces same into the groove 22. The extreme edge of the edge portion 23 is turned around the clamp ring 24 (see Fig. 2). The bag 10 is constructed relatively thick at the neck portion 11 so that this portion does not expand materially during inflation. The main portion of the bag 10 is thin so as to be capable of inflating, as indicated by the dot and dash lines 10 in Fig. 1.

In Fig. 3 a modified form of the invention has been disclosed which distinguishes from the prior form merely in the fact that a relatively short tube 25 is connected with the neck portion 11 of the bag 10. In other respects this form of the invention is identical to the prior form and identical parts have been indicated by like reference numerals. A hard rubber tip may be inserted into this tube 25. The tube 25 flares slightly at its top in order to prevent the rubber pipe connector 18 from falling off. The pipe connector 18 is used by turning it inside out to extend upwards, as indicated by the dot and dash lines 18. Then the bag 10 may be filled in the same way previously described.

The operation and use of the new catheters may be understood from the following:

The connector 18 is used to fill the bag 10 with liquid and suitable medication. While the liquid enters the bag 10 the force of the liquid keeps the ball 16 out of the neck portion 11. The bag 10 becomes inflated so as to hold a larger quantity of the medicated liquid. When sufficient liquid has entered the bag the supply is turned off. Immediately, the ball 16 floats upwards and becomes wedged in the neck portion 11, sealing the bag 10 so as to retain the liquid. If the catheter is of the type shown in Fig. 3, a suitable tip is inserted in the pipe 25. If it is of the type shown in Fig. 1 the connector 18 is merely slipped down to its original position, shown by the full lines on the drawing, and it is ready to be used. The nozzle or tip is inserted in a body cavity in the usual way. Then the ball 16 is slipped downwards with the fingers through the flexible neck portion 11 so that the liquid is free to discharge through the nozzle or tip.

While I have illustrated and described the preferred embodiments of my invention, it is to be understood that I do not limit myself to the precise constructions herein disclosed and the

right is reserved to all changes and modifications coming within the scope of the invention as defined in the appended claims.

Having thus described my invention, what I claim as new and desire to secure by United States Letters Patent is:

1. In a catheter having a rubber bag which may be inflated with a liquid under pressure, said rubber bag having at its top a flexible neck portion to which a nozzle may be connected, said neck portion having downwardly and outwardly tapering sides sufficiently flexible to be deformed by one's fingers engaging the outside face of said neck portion, a light ball which will float in said liquid and become wedged into said tapering flexible sides of said neck portion when said bag is filled with said liquid to its neck portion so as to confine said liquid in said bag, and said neck portion being sufficiently flexible so that said ball may be manually forced downwards out of said neck portion by flexing said neck portion with the fingers engaging the outside of said neck portion in order to release said confined liquid.

2. In a catheter having a rubber bag which may be inflated with a liquid under pressure, said rubber bag having at its top a neck portion to which a nozzle may be connected, said neck portion having downwardly and outwardly tapering sides, a light ball which will float in said liquid and become wedged into said tapering sides of said neck portion when said bag is filled with said liquid to its neck portion so as to confine said liquid in said bag in a manner so that said ball may be manually forced downwards out of said neck portion by flexing said neck portion with the fingers in order to release said confined liquid, and means for connecting a supply of liquid with said neck portion, comprising a tube connected with said neck portion, and a rubber pipe connector on said tube, said tube terminating in a nozzle, said pipe connector being of frusto-conical shape and slidably mounted on said tube, and said pipe connector being flexible in order that it may flex into a diverging position when it is at the outer end of said tube and may be flexed into a convex position to engage over said neck portion when it is at the inner end of said tube.

3. In a catheter having a rubber bag which may be inflated with a liquid under pressure, said rubber bag having at its top a neck portion to which a nozzle may be connected, said neck portion having downwardly and outwardly tapering sides, a light ball which will float in said liquid and become wedged into said tapering sides of said neck portion when said bag is filled with said liquid to its neck portion so as to confine said liquid in said bag in a manner so that said ball may be manually forced downwards out of said neck portion by flexing said neck portion with the fingers in order to release said confined liquid, and means for connecting a supply of liquid with said neck portion, comprising a tube connected with said neck portion, and a rubber pipe connector on said tube, said tube being of rubber and terminating in a nozzle, and a stiffening tube mounted coaxially of said tube.

4. In a catheter having a rubber bag which may be inflated with a liquid under pressure, said rubber bag having at its top a neck portion to which a nozzle may be connected, said neck portion having downwardly and outwardly tapering sides, a light ball which will float in said liquid and become wedged into said tapering sides of said neck portion when said bag is filled with said liquid to its neck portion so as to confine

said liquid in said bag in a manner so that said ball may be manually forced downwards out of said neck portion by flexing said neck portion with the fingers in order to release said confined liquid, said bag having an opening through which said ball may be inserted into said bag, and means for closing said opening, comprising a plug with a peripheral groove, the edge portion of said opening engaging said groove, and a clamp ring clamping said edge portion into said groove.
